UNITED STATES PATENT OFFICE.

WILLIAM WILKIE, OF DENNISTOUN, GLASGOW, SCOTLAND.

APPLIANCE FOR PRESSING THE COLLARS OF ARTICLES OF WEARING-APPAREL.

1,229,366.

Specification of Letters Patent.

Patented June 12, 1917.

Application filed March 19, 1917. Serial No. 155,906.

To all whom it may concern:

Be it known that I, WILLIAM WILKIE, of 34 Garthland Drive, Dennistoun, Glasgow, Scotland, have invented a certain new and useful Appliance for Pressing the Collars of Articles of Wearing-Apparel, of which the following is a specification.

My invention relates to an appliance for pressing and shrinking wearing apparel. 10 There is a known type of machine in which a fixed ironing bed (which may be conical) is mounted on a frame and cooperates with a vertically or laterally-moving ironing plate (also conical) operated by a treadle 15 mounted on the stand in order to hot-press articles placed between them.

It is accordingly the principal object of my invention to provide means in the type of machine just mentioned for conveniently 20 pressing the collar of a garment.

Further objects of my invention will appear from the detailed description hereinbelow and from the appended claims.

In order that my invention may be properly understood and readily carried into effect, I have hereunto appended one sheet of drawings of which—

Figure 1 is a front view of the machine embodying my invention.

30 Fig. 2 is a side elevation of the same, and Fig. 3 is a detached view of presser plate, heated bed, and movable curved plate with the article under treatment in position, all hereafter more fully referred to and described.

Referring to the drawings, A is the framework. B is the treadle mounted in said framework and C is the table. D is the stationary presser plate bolted thereto 40 by bracket E. F is an overhead bracket fitted thereto by bolts. G is the long curved lever pivoted within the jaws F¹ of the bracket. The long lever extends from the top of the machine to the bottom at or near 45 which it is attached to the treadle bar B¹.

The upper surface of treadle bar B¹ is formed with ratchet teeth B². Engaging with said teeth B² is a pivoted rod or pawl H depending from the frame of the machine at the front thereof. I is the lever of fork formation pivoted to the aforesaid overhead bracket at I¹. J is a weight attached to the lever I at the outer end. K is a movable heated presser plate pivotally attached to the lever at its hollow end I². The tendency of the heated presser plate is

to rise to the position shown in dotted lines in Fig. 2 due to the weight J. L is a short depending rod or ram pivoted to the upper end of the long lever G aforesaid. This rod 60 or ram L is designed to fall into the vertical position as shown, and engage the upper end of the heated presser plate K which is maintained under pressure by such engagement. M is a movable curved plate hinged 65 to the front of the machine at M¹. The plate is pressed with the curved surface into engagement with the stationary presser plate D with the article N, (as for example the upper part of a jacket or coat with its 70 lapel folded over the plate M) interposed therebetween, as seen in Fig. 3. The movable heated bed is lowered into position and cooperates with the plate M and stationary presser D, and the treadle is depressed by 75 the foot, the short depending bar co-acting on the head of the heated presser plate K. The pressing operation being completed, the treadle is released by pulling on the spring F so as to remove the pawl H from engagement with the teeth B². The spring O attached to the treadle rod and under frame of the machine restores the treadle B to the position shown in dotted lines, enabling the treated articles to be withdrawn and re- 80 placed by others requiring treatment.

Claims:

1. In appliances for pressing and shrinking wearing apparel, a conical stationary presser plate mounted on the table of the 90 machine, around which the article under treatment is placed, a curved movable plate for shaping and pressing the collar of said article under treatment, and a conical movable heated presser plate enveloping the beforementioned presser plates for exerting pressure in the pressing, operating substantially as and for the purposes hereinbefore described and illustrated on the accompanying sheet of drawings. 100

2. In appliances for pressing and shrinking wearing apparel, a framework of taper formation, a treadle inserted in said framework, a table surmounting said framework, a stationary presser plate mounted on said 105 table, an overhead bracket bolted to said table, a long curved lever mounted at its upper end in said bracket, and connected at its lower end with the treadle bar, a depending bar pivoted to the upper part of said 110 curved lever, a conical movable heated plate movable above and engaging with the sta-

stationary presser plate, means by which said movable presser plate is raised and lowered consisting of a forked lever pivoted to the bracket bolted to table aforesaid and controlled by a depending weight, and a spring fitted beneath the table of the machine and attached to the treadle bar which is designed to raise the ram or bar from engagement with the stationary presser plate, substan-

tially as and for the purposes hereinbefore described and illustrated on the accompanying sheet of drawings.

In witness whereof I affix my signature in presence of two witnesses.

WILLIAM WILKIE.

Witnesses:

JOHN LIDDLE,
JOHN TRAIN LIDDLE.
